UNITED STATES PATENT OFFICE.

EDWIN C. WALLACE, OF EAST AUBURN, CALIFORNIA.

PROTECTING-SHEET.

1,107,732.

Specification of Letters Patent. Patented Aug. 18, 1914.

Application filed May 3, 1911. Serial No. 624,867.

To all whom it may concern:

Be it known that I, EDWIN C. WALLACE, citizen of the United States, residing at East Auburn, in the county of Placer and State of California, have invented certain new and useful Improvements in Protecting-Sheets, of which the following is a specification.

My invention relates to a process of water-proofing a normally non-waterproof porous body, and to the product obtained by the practice of the process.

Broadly, my invention consists in taking a normally non-waterproof porous body, formed of concrete or wood or the like, also cloth or roofing felt, and first subjecting it to the action of a preferably waterproofing liquid adapted to enter the pores of the body by capillary action, and subsequently applying to the body thus treated a waterproofing material, normally incapable of entering the pores of the body, but properly entering said pores in the presence of the previously applied liquid, by the process of diffusion, caused by the same being partly or wholly dissolved by the previously applied liquid.

Specifically, over a surface of oil treated material is applied a heavy viscous mixture of hydrocarbons which may be of an oily, waxy or bituminous nature. Under normal conditions this heavy viscous material is practically devoid of penetrating qualities but when coated over the mobile oil treated surface permeates and penetrates the mass by the process of diffusion. It should be explained that the heavy viscous materials are all mixtures of hydrocarbons which by the process of diffusion are partially separated, the more diffusive constituents penetrate farther into the mass, while the heavier less diffusive constituents are retained in the outer interstices or pores of the mass, clogging them and forming an effective protective coating. Under certain conditions it may be advisable to cover this by a non-adhesive material to prevent the protective coating from adhering to anything which may come into contact with it.

In the accompanying drawing the figure is a transverse sectional view of the product such as may be used upon railway ties.

As illustrated in the drawing, the foundation or body is indicated by the reference numeral 1. This body may be wood, concrete, or any other substance or material. Upon the surface of this body is applied a

coating of light penetrating hydro-carbon oil, indicated at 2. This oil enters into the grain or interstices of the body 1 and forms a bonding agent for the water-proofing surface, indicated at 3. This surface 3 is a heavy viscous composition of hydrocarbons including more or less asphalt which under normal conditions possesses little or no penetrating qualities, but is of such nature as to be effectively water-proof. This coating of heavy viscous composition of hydrocarbons 3 is partially dissolved by the light oil 2, and consequently the portions so dissolved follow the light oil into the grain or interstices of the body and constitute means whereby the said coating 3 tenaciously clings to the body 1.

In some instances, it is desirable to provide the coating 3 with non-adhesive protecting material, and for railway ties may consist of sand, stone-screenings, plaster, or earthy matter, but when applied to walls, floors, or other bodies may be made of any material consonant with the purpose. In the drawing this material is indicated at 4.

By applying the mobile oil to a surface having voids and allowing the oil to enter the voids or pores of the body and then applying a viscous material or oil of bituminous nature the latter permeates the body by diffusion and fills the voids or pores even though the entrances to the voids or pores are of less diameter than the major portions of the said voids or pores. Thus the fusible element is anchored in position in the voids or pores of the surface of the body.

Having thus described the invention, what is claimed as new is:

1. The herein described process of water-proofing a non-waterproof porous body, which consists in first impregnating the pores thereof with a waterproof liquid adapted to readily enter said pores by capillary action, and subsequently applying a viscous waterproofing substance normally incapable of entering said pores and soluble in said liquid, to said body, in the presence of said liquid for the purpose of causing the viscous substance to dissolve in said liquid and enter the pores of the body by the process of diffusion.

2. The herein described process of water-proofing a non-waterproof porous body, which consists in first and separately applying to the said body a waterproofing liquid

adapted to readily enter the pores of the body by capillary action, and subsequently and separately applying to said body a fluid waterproofing substance incapable alone of 5 entering said pores and soluble in said liquid, in the presence of said liquid for the purpose of causing the waterproofing fluid to dissolve in the waterproofing liquid already contained within the pores of the 10 body, by the process of diffusion.

3. The herein described process of waterproofing a non-waterproof porous concrete body, which consists in first applying to the porous concrete body a light waterproofing 15 oil adapted to readily enter said pores by capillary action, and subsequently applying to the porous body thus treated a heavy viscous waterproofing oil, which is soluble in the light oil and normally incapable of entering the pores of the body but entering 20

said pores in the presence of the light oil by the process of diffusion.

4. The herein described process of waterproofing a non-waterproof porous body, which consists in first impregnating the 25 pores of the body with a light waterproofing liquid adapted to enter the pores by capillary action, and subsequently applying without pressure a heavy waterproofing fluid to the porous body to contact with the 30 outer portion of the light liquid impregnating the pores of the body, to be led thereby by the process of diffusion into said pores.

In testimony whereof I affix my signature in presence of two witnesses.

EDWIN C. WALLACE.
